UNITED STATES PATENT OFFICE.

WILLIAM H. VOSS, OF DAVENPORT, IOWA.

GEARING FOR WASHING-MACHINES.

SPECIFICATION forming part of Letters Patent No. 794,823, dated July 18, 1905.

Application filed December 27, 1904. Serial No. 238,392.

To all whom it may concern:

Be it known that I, WILLIAM H. Voss, a citizen of the United States, and a resident of Davenport, in the county of Scott and State 5 of Iowa, have invented certain new and useful Improvements in Gearing for Washing-Machines, of which the following is a full, clear, and exact specification.

The object of my invention is to provide a 10 simple mechanical movement for converting a continuous rotary movement into a rotary reciprocal movement for washing-machines, which utilizes the power applied to operate it in such manner that heavy work can be performed by the rotary reciprocal stirrer-shaft 15 with the least possible effort. This I accomplish by the means hereinafter fully described and as particularly pointed out in the claims.

20 In the drawings, Figure 1 is a side elevation of the cover of a washing-machine tub with my improvements applied thereto. Fig. 2 is a plan view of the same with parts of the cover and supporting-frame broken away.

25 Referring to the drawings, A represents the cover of a tub of a washing-machine, and B represents the base-plate of a supporting-frame C, which bridges over the same from end to end and affords bearings for the operative parts of my invention. The base-plate is arranged in a diametrical position on the cover, and the vertical portion of the supporting-frame arising from the end thereof nearest the circumferential edge of said cover 30 is provided with horizontal bearings *a* for the continuously-revolving drive-shaft D. The inner end of drive-shaft D is provided with a beveled drive-gear E, which engages a larger beveled gear F, secured on the lower 35 end of a vertical spindle G, which latter is journaled in vertical bearings *b* in the horizontally-disposed reach of the supporting-frame.

40 Pivotally secured to the cover at a point a suitable distance to one side of the vertical plane of the axis of the drive-shaft is a horizontal arm H, which extends under gear F and in the portion thereof working under said gear has a longitudinal slot *c*, which is entered 45 and engaged by a stud *d*, secured to and de-

pending from gear F. Arm H has a member projecting back at an acute angle thereto, which extends horizontally from the end thereof nearest gear E, and the edge of this arm farthest from the pivot of arm H is provided with a rack *e*, which latter meshes with an eccentric pinion J, fast on the stirrer-shaft K. This stirrer-shaft is journaled in suitable bearings in both the overhead horizontal reach of the supporting-frame C and the base-plate B thereof, and it extends down through the latter and through the cover A and has a suitable stirrer-head connected to its lower end.

In operation the drive-shaft is revolved continuously in a given direction and imparts its motion, through the medium of gear E, to gear F. The latter through stud *d* vibrates arm H back and forth, and the rack *e* of the latter engages and rotates pinion J and stirrer-shaft K first in one direction and then in the other.

What I claim as new is—

1. In a washing-machine, the combination with a suitable supporting-frame, a continuously-revolving drive-shaft journaled therein, 75 a pinion on one end thereof, a gear suspended from said supporting-frame the axis of which is at right angles to said drive-shaft, which is engaged by said pinion and has a stud projecting from its face, a pivoted arm movable 80 in a plane transaxial to said gear, and having a longitudinal slot engaged by said stud, a rack projecting from said arm at an angle thereto, a stirrer-shaft and an eccentric pinion thereon engaged by said rack. 85

2. In a washing-machine, the combination with an overhead-supported continuously-revolving horizontally-disposed gear, and a vibratory arm actuated thereby and having a rack projecting at an angle from the same, of 90 a rotary reciprocal stirrer-shaft, and an eccentric pinion thereon engaged by said rack.

3. In a washing-machine the combination with a supporting-frame comprising upright end portions and a horizontal portion connecting the upper ends of the same, and a continuously-revolving horizontally-disposed gear, the bearings of which are suspended from the horizontal portion of said supporting-frame, 95 of a vibratory arm movable horizontally un- 100

der said gear and actuated thereby and having a rack projecting laterally therefrom at an angle, a vertically-disposed rotary reciprocal stirrer-shaft, and an eccentric pinion thereon engaged by said rack.

4. In a washing-machine the combination with a supporting-frame comprising upright end portions and a horizontal portion connecting the upper ends of the same, and a continuously-revolving horizontally-disposed gear, the bearings of which are suspended from the horizontal portion of said supporting-frame, a stud secured to and projecting downward therefrom, of a vibratory arm movable horizontally under said gear and having a longitudinal slot therein which is engaged by said stud, and having a rack projecting laterally therefrom at an angle; a vertically-disposed rotary reciprocal stirrer-shaft, and an eccentric pinion thereon engaged by said rack.

5. In a washing-machine the combination with a supporting-frame comprising upright end portions and a horizontal portion connecting the upper ends of the same, a continuously-revolving drive-shaft journaled in one of the upright ends of said frame, a pinion on the inner end of the same, a horizontally-disposed gear the bearings of which are suspended from the horizontal portion of the supporting-frame and which is engaged by said pinion, a stud secured to and projecting downward therefrom, of a vibratory frame movable horizontally under said gear and having a longitudinal slot therein which is engaged by said stud and having a rack projecting laterally therefrom at an angle, a vertically-disposed rotary reciprocal stirrer-shaft, and an eccentric pinion thereon engaged by said rack.

tally under said gear and actuated thereby and having a rack projecting laterally therefrom at an angle, a vertically-disposed rotary reciprocal stirrer-shaft, and an eccentric pinion 35 thereon engaged by said rack.

6. In a washing-machine the combination with a supporting-frame comprising upright end portions and a horizontal portion connecting the upper ends of the same, a continuously-revolving drive-shaft journaled in one of the upright ends of said frame, a pinion on the inner end of the same, a horizontally-disposed gear the bearings of which are suspended from the horizontal portion of the supporting-frame and which is engaged by said pinion, a stud secured to and projecting downward therefrom, of a vibratory frame movable horizontally under said gear and having a longitudinal slot therein which is engaged 40 by said stud and having a rack projecting laterally therefrom at an angle, a vertically-disposed rotary reciprocal stirrer-shaft, and an eccentric pinion thereon engaged by said rack.

In testimony whereof I have hereunto set 55 my hand this 21st day of November, A. D. 1904.

WILLIAM H. VOSS.
